UNITED STATES PATENT OFFICE

151,105

DESIGN FOR A DISPLAY SIGN

Erwin C. Uihlein, Grafton, Wis., assignor to Jos. Schlitz Brewing Company, Milwaukee, Wis., a corporation of Wisconsin

Application March 13, 1946, Serial No. 127,437

Term of patent 14 years

(Cl. D1—12)

To all whom it may concern:

Be it known that I, Erwin C. Uihlein, a citizen of the United States residing at the town of Grafton, in the county of Ozaukee, and State of Wisconsin, have invented a new, original, and ornamental Design for a Display Sign, of which the following is a specification, reference being had to the accompanying drawing, forming part thereof.

Viewed from the rear and bottom my display sign is plain. The characteristic feature of my design resides in the ornamental matter appearing on the face of the sign.

I claim:

The ornamental design for a display sign, as shown and described.

ERWIN C. UIHLEIN.
